UNITED STATES PATENT OFFICE.

CHRISTOPHER J. MEYER, OF MILWAUKEE, WISCONSIN, ASSIGNOR TO EVINRUDE MOTOR COMPANY, OF MILWAUKEE, WISCONSIN, A CORPORATION OF WISCONSIN.

STEERING AND REVERSING TILLER.

1,191,211.

Specification of Letters Patent.

Patented July 18, 1916.

Application filed March 1, 1915. Serial No. 11,415.

To all whom it may concern:

Be it known that I, CHRISTOPHER J. MEYER, a citizen of the United States, residing at Milwaukee, county of Milwaukee, and State 5 of Wisconsin, have invented new and useful Improvements in Steering and Reversing Tillers, of which the following is a specification.

My invention relates to improvements in 10 steering and reversing tillers, and pertains especially to that class of tillers which are employed in connection with small motor driven propelling apparatus, such as detachable row boat motors and in which the 15 boat is guided to some extent at least by swinging the tiller from side to side and thereby effecting a corresponding swinging movement at the axis of the propeller wheel. Propelling apparatus of the general type 20 above referred to is shown in Letters Patent of the United States, numbered 1001260, dated August 22nd, 1911, issued to O. Evinrude for a marine propulsion mechanism.

The object of my invention is to provide 25 a controlling tiller, which may be manipulated to release the propeller supporting shaft and automatically reengage it when the propeller has been rotated by its own side thrust to a reversed position, whereby a 30 series of reversing operations may be performed in succession and the propeller accurately positioned for either forward or backward propulsion without in any way affecting the functions of the tiller for steering 35 purposes.

In the drawings—Figure 1 is a plan view 40 of my improved tiller lever with a portion of the casing broken away to show the reversing slide and catch mechanism. Fig. 2 is a side elevation of my improved tiller as applied to a propeller supporting shaft and propeller, a portion of the tiller and shaft being shown partially in vertical section, exposing the driving shaft. Fig. 3 is a sectional view, drawn on line $x-x$ of Fig. 1. Fig. 4 is a view of the tiller head as seen 45 from below. Fig. 5 is a plan view, partly in horizontal section, of a tiller embodying my invention in modified form. Fig. 6 is a 50 side view of the same.

Like parts are identified by the same reference characters throughout the several views.

In Fig. 1, 1 is a propeller supporting shaft, 2 is a gear casing carried thereby, and 55 3 are the propeller blades. These parts may be assumed to be of ordinary construction.

The gear casing is provided with a downwardly extending rudder member 5. A clamping sleeve 7 is secured to the upper 60 end portion of the supporting shaft 1. The lower end portion of this sleeve is preferably slit and provided with clamping ears 8, whereby the same may be securely bound upon the supporting shaft 1. The supporting shaft is tubular and a driving shaft 9 extends downwardly therethrough. The clamping sleeve 7 is provided with a cam projection 12 at its upper end. A tiller lever 13 is provided with a tiller head 14, having 70 a depending sleeve 15 through which the clamping sleeve 7 extends. The tiller head is provided with an interior cavity 16 to receive the cam projection 12, and a slide 17 in this cavity is adapted to serve as a latch 75 to control rotative movements of the cam. This slide latch 17 is provided with an aperture 19 to receive the upper end of sleeve 15 and cam projection 12. The walls of aperture 19 are provided with shoulders 21 80 and 22 located diametrically opposite each other across the axis of the propeller supporting shaft 1 and driving shaft 9, and the dimensions of the aperture 19 are such that the cam projection 12 will necessarily engage one of these shoulders 21 or 22, when the slide is in a position to allow the cam projection 12 to pass the other shoulder in a 85 rotative movement of the propeller supporting shaft 1.

Therefore assuming the parts to be in the 90 position in which they are shown in Fig. 1, a forward movement of the slide latch 17 to withdraw shoulder 21 from engagement with cam 12, will allow a rotative movement 95 of cam 12, sleeve 7, shaft 1, and the propeller, until these parts have revolved a half turn, whereupon said cam 12 will strike shoulder 22 and prevent further movement, said shoulder 22 having been moved forwardly simultaneously with the forward 100 movement of shoulder 21 and both of these shoulders being carried by the slide 17. The side thrust of the propeller due to the action of the driving gears, will prevent rotative 105 movements in the opposite direction.

The slide latch is actuated from a handle 25 mounted upon an outer extension 26 of the lever 13 and adapted to serve not only as a handle, but by rotative adjustment to determine the position of the slide latch 17. A rotative movement of the handle 25 is communicated to the slide latch 17 through a slotted tubular coupling member 27, cross pins 28 engaged in helical guide slots 29 in the coupling member 27, and a stem 30, which carries the cross pins and is also connected with the latch 17. The member 27 is releasably secured to the member 26 of the handle lever by a spring actuated pin 31. A spring 33 is interposed between a collar 34 on the stem 30 and an interior annular stop flange 35 on the lever section 13. This spring tends to give stability to the latch and its connections while permitting the described movements. It will be observed that the forward end of lever section 13 seats against a shoulder at 40 in the member 27. Therefore when this coupling member 27 is rotated, it has a thrust bearing at 40 on the handle section 13. A pin or screw 37 carried by member 27, engages a segmental slot 38 in the outer portion of lever section 13 and not only prevents longitudinal movements of the outer section 26 thereon, but also limits the rotative movements of the handle.

Referring to Figs. 5 and 6, which show the modified form of tiller, it will be observed that the slide latch 17 is connected with a stem 30^a, the forward end of which is screw threaded, as illustrated at 41, and has threaded engagement with a nut 42. The handle 25^a is connected with an outer lever section 26^a corresponding in function with the section 26, shown in Figs. 1 and 2, and detachably connected with a collar 27^a having coupling connection with a nut 42. This coupling may be made in any suitable manner. In the drawings I have illustrated a screw connection, comprising screws 44 extending through segmental slots 45 in the inner lever section 13^a and having threaded engagement with the nut 42. In this construction, the slide latch 17 may be moved in either direction by rotating the handle 25^a, stem 30^a being moved to the front and rear by the rotation of the nut 42 thereon. The length of the slides 45 limits the extent of the rotative movement of the nut, but the pitch of the screw threads is so proportioned to the length of the slots 45, that the movement will be sufficient to adjust the slide latch 17 to its two positions, as above described. Owing to the fact that the screws 44 extend through the segmental slots 45, it is obvious that relative forward or backward movements of collar 27^a on lever section 13^a will be prevented. A spring actuated pin 31 is employed to lock the collar 27^a to the lever section 26^a in the same manner as above described with refer-

ence to Figs. 1 and 2. It will be observed that the spring 46 is socketed in collar 27^a and is compressed by a nut 47.

In each of the above forms of construction, the tiller lever may be used in the ordinary manner for steering purposes. When it is desired to reverse the direction of propulsion, the handle is rotated to release the cam projection 12 from the engaged shoulder on the slide latch, whereupon the propeller instantly and automatically rotates to the reversed position by said thrust of the propeller blades upon the water. The propeller is then held in the reversed position by the opposing shoulder on the latch, which engages the cam projection upon completion of a one-half turn of the propeller and its supporting shaft. To secure a return of the propeller to its original position, it is merely necessary to rotate the handle to its first position, thereby again releasing the cam for a second one-half turn in the same direction.

It is desirable to counteract the effect upon the tiller of the lateral thrust pressure exerted by the propeller driving connections which tend to rotate the propeller about the axis of the vertical driving shaft 9 as above described. I therefore provide the tiller head 14 with a depending segmental flange 51. A spring 48 connects one end of the flange with a supporting transom bracket or frame 50 (Fig. 4), similar to that illustrated in said former Patent, No. 1001260, as employed for connecting the propelling mechanism with a row boat transom. The spring 48 exerts its tension in opposition to the lateral thrust of the propeller, and substantially counteracts the thrust of the gears as transmitted to the tiller lever, thereby substantially relieving the operator from the necessity of exerting a constant holding pressure upon the lever to prevent it from swinging. The curved flange 51 provides a bearing for the spring and its tension is therefore exerted at all times in a direction substantially along the line of thrust pressure, although the lever may be swung from side to side for steering purposes.

I claim—

1. A tiller provided with a releasing latch, and an operating handle, adapted, by rotation upon its own axis, to actuate the latch from one latching position to another on the opposite side of the axis about which the tiller swings.

2. The combination with a propeller supporting shaft, of a tiller in latch connection with said shaft, and a tiller operating handle having a longitudinally movable member operatively connected with the latch.

3. The combination with a propeller supporting shaft, of a catch connected therewith, a slide latch having an aperture to receive the catch and also provided with a set of catch engaging shoulders, and a tiller

lever provided with a guide for the latch and having a handle connected with the latch and adapted to be manipulated to move the latch to positions for selective engagements of said shoulders with the catch.

4. A reversible boat propelling mechanism, including the combination of a propeller, a propeller supporting shaft adapted to rotate during reversing movements of the 10 propeller, and a slide having an aperture to receive the upper end of said shaft, said slide being adapted to engage the shaft in either one of two positions of shaft and slide adjustment.

15 5. A reversible boat propelling mechanism, including a propeller supporting shaft provided at its upper end with an outwardly projecting catch, a tiller lever provided with a movable latch adapted to engage the catch 20 on opposite sides of the shaft, and an operating handle, on the tiller lever, having an independent latch adjusting connection.

6. A reversible boat propelling mechanism including a propeller supporting shaft 25 provided with a tiller engaging member having an outwardly projecting catch, in combination with a tiller having a slide latch provided with a set of catch engaging members located on diametrically opposite sides 30 of said shaft, and so spaced that one or the other of said members will engage the catch in any position of slide adjustment.

7. A reversible boat propelling mechanism including a propeller supporting shaft 35 provided with a tiller engaging member having an outwardly projecting catch, in combination with a tiller having a slide latch provided with a set of catch engaging members located on diametrically opposite sides 40 of said shaft, and so spaced that one or the other of said members will engage the catch in any position of slide adjustment, and a tiller operating handle provided with means for actuating said slide to selectively position said members for engagement with the catch.

8. A reversible boat propelling mechanism including a propeller supporting shaft provided with a tiller engaging member 50 having an outwardly projecting catch, in combination with a tiller having a slide

latch provided with a set of catch engaging members located on diametrically opposite sides of said shaft, and so spaced that one or the other of said members will engage 55 the catch in any position of slide adjustment, a tiller operating handle adapted to rotate upon its own axis, and connections between the handle and slide adapted to utilize rotative movements of the handle to 60 actuate the slide.

9. A reversible boat propelling mechanism including a propeller supporting shaft provided with a tiller engaging member having an outwardly projecting catch, in 65 combination with a tiller having a slide latch provided with a set of catch engaging members located on diametrically opposite sides of said shaft, and so spaced that one or the other of said members will engage 70 the catch in any position of slide adjustment, a tiller operating handle adapted to rotate upon its own axis, a slide actuating rod, and a helical guide connected with the handle and loosely engaging the rod, where- 75 by a rotative movement of the handle will be transmitted to move the rod longitudinally.

10. The combination with a boat propelling mechanism, including a propeller and 80 an upright propeller supporting shaft, a propeller actuating shaft extending therethrough, of a support for said propelling mechanism, a tiller connected with the propeller supporting shaft, and a spring connecting the upright shaft with the support and adapted to resiliently oppose the tendency of the propeller to revolve about the axis of its supporting shaft. 85

11. The combination of a boat propelling 90 mechanism, a supporting bracket therefor, a tiller lever, and a spring connecting the lever with the supporting bracket in a position to exert its tension in opposition to lateral thrust exerted by the propelling mechanism. 95

In testimony whereof I affix my signature in the presence of two witnesses.
